CLAIM

The ornamental design for display clip for attachment to the waistband of trousers for displaying size of garment and other information, as shown and described.

DESCRIPTION

FIG. 1 is a view in perspective of display clip for attachment to the waistband of trousers for displaying size of garment and other information showing my new design, with the waistband and fragmentary portion of a pair of trousers shown in broken lines for illustrative purposes only and forming no part of the claimed design; the clip being applied to the waistband of a pair of trousers (indicated in broken lines) for display in a retail store; FIG. 2 is a front elevational view thereof; FIG. 3 is a rear elevational view thereof; FIG. 4 is a side elevational view thereof.

FIG. 1

FIG. 2

FIG. 3

FIG. 4
